UNITED STATES PATENT OFFICE.

JAMES J. MORGAN, OF CHICAGO, ILLINOIS.

PROCESS OF MANUFACTURING ALCOHOL FROM GARBAGE.

1,114,017.

Specification of Letters Patent.

Patented Oct. 20, 1914.

No Drawing.

Application filed September 20, 1909. Serial No. 512,478.

To all whom it may concern:

Be it known that I, JAMES J. MORGAN, a citizen of the United States, residing at Chicago, Cook county, Illinois, have invented a new and useful Process of Manufacturing Alcohol from Garbage, of which the following is a specification.

My invention relates to the process of manufacturing alcohol and the object thereof is to provide a comparatively simple and efficient process of manufacturing alcohol from garbage or similar refuse.

Speaking in general terms, my process consists in first converting the carbohydrates contained in the garbage to glucose by the action of a dilute mineral acid and then converting the glucose so obtained to alcohol by fermentation.

In practice, the garbage is reduced by preference to a homogeneous mass by crushing or grinding the same in suitable manner and the same being introduced in a suitable container is mixed thoroughly with a dilute solution of a mineral acid such as sulfuric, hydrochloric or nitric acid. The mass is thereupon heated to or near the temperature of boiling water and such temperature is maintained until such time as the numerous carbohydrates present in the garbage are converted to glucose. The mass or solution thus obtained contains glucose, free mineral acid and free organic acids originally present and also the free organic acids released from combination by the addition of a mineral acid. This mass or solution is thereupon neutralized by a suitable neutralizing agent such as for instance lime, marble dust, lye, etc. The mass is thereupon cooled to a proper temperature, such as for instance 60 to 70 degrees F. and is then mixed with a suitable quantity of brewers' yeast and allowed to ferment. The alcohol thus formed is recovered by distillation in the usual manner.

Referring to a typical operation as an example, a given weight of garbage is reduced to a homogeneous mass in suitable manner as by crushing or grinding, and, being then introduced into a container, is mixed thoroughly with from five to ten times its weight of a substantially 2% solution of sulfuric acid. This acid is used by preference because when neutralized the resulting product has practically no effect upon the subsequent fermentation. The strength of the acid so employed may vary

according to the composition of the garbage under treatment. In general, it may be said that the more inorganic matter (bone, salts, etc.) present, the stronger the acid required. The mixture which results from the above treatment and which should be of sufficient fluidity to permit of boiling, is now introduced into a suitable vat or container and its temperature brought to or near the boiling point. This temperature is maintained for forty-five minutes at the end of which time a small quantity of the liquid is withdrawn and the amount of dextrose therein determined. The boiling is still continued and quantitative tests of the dextrose present are made at intervals of ten or fifteen minutes. When at length two successive tests fail to show any considerable increase of dextrose the conversion may be considered complete. This result will occur in about one and a half to two hours. The fluid mass which now contains the fermentable sugars, free sulfuric acid, free organic acids which have been released from their combinations by the stronger mineral acid, and the changed and unchanged residue, is thereupon introduced into suitable vats and neutralized by the addition of lime. The neutralization is necessary at this point inasmuch as the presence of even small quantities of either organic or inorganic acids renders the subsequent fermentation slow and incomplete. Lime is selected for the neutralizing agent since the resulting sulfate is less soluble and has less injurious action on the subsequent fermentation than the salts of soda or potash, for instance. The fluid is now allowed to cool to about 70 degrees F. and brewers' yeast is added in considerable proportion, preferably one pound thereof to the barrel of liquid. Fermentation is then allowed to proceed and the solution tested for dextrose from time to time. When the dextrose has practically disappeared, fermentation may be considered complete, this step in the process usually occupying from five to nine days. The fluid mass is then conducted to a suitable distilling apparatus and the alcohol recovered and refined in the usual manner.

It will be understood that I use the term "glucose" in the scientific sense as referring to the fermentable sugars (dextrose, and laevulose) as distinguished from the glucose of the trade in which instance the term "glucose" is applied to the product obtained

by the conversion of starch and the subsequent refining thereof into the merchantable glucose.

In the described process of manufacturing alcohol from garbage it is necessary before fermentation takes place to remove from the mass or solution the free mineral and organic acids referred to inasmuch as their presence has a strong and deleterious effect upon alcohol fermentation, making the operation of fermentation extremely slow and incomplete in proportion to the quantities of the acids present.

By my process I am enabled to utilize garbage and the like for the production of alcohol in a very simple and inexpensive manner.

I claim:

1. The process of manufacturing alcohol from garbage which consists in introducing into a mass of garbage a dilute solution of mineral acid and subjecting the same to the action thereof until the carbohydrates are converted into glucose, neutralizing said acid and other acid or acids present after such conversion, then introducing a fermenting agent, and finally recovering the alcohol by distillation; substantially as described.

2. The process of manufacturing alcohol from garbage which consists in introducing into a mass of garbage a dilute solution of mineral acid and heating the same and subjecting such mass of garbage to the action of the acid until the carbohydrates are converted into glucose, neutralizing said acid and other acid or acids present after such conversion, then introducing a fermenting agent, and finally recovering the alcohol by distillation; substantially as described.

3. The process of manufacturing alcohol from garbage which consists in introducing into a mass of garbage a dilute solution of mineral acid and heating the same to a temperature approximating the boiling point of water and subjecting it to the action of the

acid until the carbohydrates are converted into glucose, neutralizing said acid and other acid or acids present after such conversion, then introducing a fermenting agent, and finally recovering the alcohol by distillation; substantially as described.

4. The process of manufacturing alcohol from garbage which consists in introducing into a mass of garbage a dilute solution of mineral acid and subjecting the same to the action thereof until the carbohydrates are converted into glucose, adding lime for neutralizing said acid and other acid or acids present after such conversion, then introducing a fermenting agent, and finally recovering the alcohol by distillation; substantially as described.

5. The process of manufacturing alcohol from garbage which consists in reducing the garbage to a substantially homogeneous mass, mixing therewith a dilute solution of mineral acid to form a mixture of proper fluidity for boiling, heating such mixture until the carbohydrates are converted, thereupon neutralizing said acid and other acid or acids present, then introducing a fermenting agent, and finally recovering the alcohol; substantially as described.

6. The process of manufacturing alcohol from garbage which consists in reducing the garbage to a substantially homogeneous mass, mixing therewith a solution of sulfuric acid of the strength and quantity substantially as herein set forth to form a mixture of proper fluidity for boiling, heating such mixture to the boiling point until the carbohydrates are converted, thereupon neutralizing said acid substantially as herein described, then introducing a fermenting agent, and finally recovering the alcohol by distillation; substantially as described.
